(57) **CLAIM**

The ornamental design for a skateboard training device, as shown and described.

DESCRIPTION

FIG. 1 is a perspective view of my new and ornamental skateboard training device;

FIG. 2 is a top plan view thereof;

FIG. 3 is a front elevational view thereof, the rear elevation being a mirror image;

FIG. 4 is a side elevational view thereof, the other side elevational being a mirror image;

FIG. 5 is a bottom plan view thereof; and,

FIG. 6 is an exploded perspective view of the present invention in spaced relation to the bottom surface of a skateboard, wherein the skateboard and fasteners are illustrated in phantom for illustrative purposes only.
